UNITED STATES PATENT OFFICE

ELIE W. LABOMBARDE, OF NASHUA, NEW HAMPSHIRE

PAPER RECEPTACLE

Application filed June 23, 1931. Serial No. 546,287.

This invention relates to boxes, and has particular reference to that type sometimes known as berry boxes or fruit baskets. Such receptacles have usually been made of thin wood or veneering which is neither strong nor weatherproof. As is well known, the juice or stain of berries and other fruits readily passes through the thin wood commonly employed for such receptacles.

10 Letters Patent No. 1,513,608, issued to me October 28, 1924, described and claimed a paper receptacle having rib-shaped legs formed by narrow doubled portions integral with two of the side walls of the receptacle.

15 While such receptacles are practical in use, the operation of gluing and folding the said leg portions involved undesirable time and expense.

One of the objects of the present invention 20 is to provide strong and durable receptacles of the general type explained in the patent referred to, but of lesser cost of production.

When receptacles are produced according 25 to said patent, it is impractical to ship the blanks in flat condition to be then converted to set-up condition by the customers or users, because of the necessity of either stitching or adhesively connecting overlapping portions 30 of the receptacles. Therefore another object of the invention is to provide paper receptacles which can be stored or shipped in flat condition, and which can be manually converted to set-up condition without requiring any stitching or gluing, thereby 35 effecting economy in production and the costs of shipping or storage.

With said objects in view, and others which 40 will be referred to, the invention consists in the receptacles substantially as hereinafter described and claimed.

Of the accompanying drawing:—

Figure 1 is a perspective view of the blank 45 with one marginal portion folded and secured and the opposite marginal portion prior to being folded and secured.

Figure 2 is a perspective view of the completed receptacle.

Similar reference characters indicate similar parts or features in both of the views. 50 The blank from which the box or recep-

tacle is made comprises a central rectangular portion 12 (Fig. 1) which is to form the bottom of the box or basket, the blank being slit and being also creased or scored as indicated by dotted lines to form two opposite end wall sections 13 having foldable flaps 14 each of which has end tongues 15, and two opposite side wall sections 16 having end flaps 17 and marginal flaps 18, the latter having free end tongues 19. The blanks are so cut that each flap 18 has abrupt end edges 20 to serve as abutments as hereinafter explained.

When the blanks are cut, they are so slit 65 that when a blank is converted to the set-up condition illustrated by Figure 2, portions 21 thereof extend down to form legs which in use support the bottom of the receptacle a slight distance above or away from a shelf or its equivalent.

In operation, the blanks are treated with paraffine wax or suitable equivalent thereof, so that the receptacles will be moisture-proof. This is done while the blanks are flat with 75 no portions folded. Then sufficient wax is removed along the flaps 18, and preferably along the outer areas of the wall sections 16, so that when adhesive is properly applied such as indicated by the shaded area of the flap at the left of Figure 1, and said flap 80 then folded as shown at the right of said Figure 1, both of said flaps 18 will be rigidly secured. It is important that the tongues 19 shall be free and not adhesively secured to 85 anything.

The blanks so prepared are ready to be stored or shipped, and they are readily converted to the set-up condition illustrated by Figure 2, by manual operations. To so convert a blank, the two sections 16 are turned up and their end flaps 17 swung in toward each other, and the other two wall sections 13 are turned up outside the flaps 17 and their flaps 14 are folded in over the flaps 17 and over the free end tongues 19 of the other 95 two wall sections, and the ends of the tongues 15 automatically snap into engagement with the abutments 20. Such engagement locks the walls 13 so that they can not swing out, because the flaps 17 and the tongues 19 are 100

enclosed within portions of said walls, and the other two walls 16, 18, can not swing out because the upper edges of their flaps 17 and tongues 19 fit closely under the fold line portions 13, 14. This will be clear when it is understood that the blanks are so shaped that when the flaps 17 and the tongues 19 are swung in or folded, the upper edges of said flaps and tongues are parallel or in 10 alinement.

The reason for leaving the tongues unglued or free is that if they were adhesively secured to the flaps 17 (see the right hand portion of Figure 1) they would offer resistance 15 to the inward folding of the flaps 17 toward each other when setting the blanks up to receptacle form. Owing to the fact that said tongues 19 are integral with two of the side walls and are tightly enclosed between portions 20 of the other two side walls, they effect a very strong reinforcement for the four upper corners of the receptacle.

When the manually-effected conversion of the blank to receptacle condition has been 25 effected as described, it not only results in reinforcing the upper portions of the walls of the receptacle by making them double-thick, but also causes the extreme edges or tops of the walls to be smoothly rounded. 30 And such double thickness also serves to compensate for such weakening of the walls as may result from forming such ventilating openings therein as are illustrated in the drawing.

35 The ventilating openings referred to exist partly in single-thick wall areas and partly in double-thick wall portions. As illustrated, the said ventilating openings are provided by forming recesses in the edges of the flaps 40 18 and elongated openings in the wall sections 16, which recesses and openings register with each other when the flaps 18 are folded inwardly and secured. This provides boxes or receptacles which have amply strong upper 45 wall portions as just referred to, without requiring the amount of material that would have to be employed if the walls were of double-thick material throughout, and the said walls have ample provision for ventilation without being weakened by the openings therein.

If it is desired that the boxes shall be per-

manently secured in set-up condition, such result may be attained by applying staples through the flaps 14, 17, and walls 13, in a manner similar to that illustrated at *c* in my Patent No. 1,513,608 hereinbefore referred to. 70

To facilitate an understanding of the invention, the sections 13 and their flaps 14 are referred to as the end walls, and the sections 16 and their flaps 18 are referred to as the side walls of the receptacle, although the 75 drawings represent the receptacle as square. As illustrated by Figure 2, all of the walls diverge, this being the preferred form for berry boxes to enable a large number of them to be nested when empty, and to facilitate 80 the filling and emptying when the contents are of a berry type.

An important feature of my invention resides in the fact that when the blank is set up to receptacle form, the upper edges of the 85 tapering end flaps 17 of the side wall sections 16 extend along and snugly fit the inner surfaces of the folds of the end wall flaps 14, and therefore resist tendency of the flaring 90 side walls to swing outwardly so as to permit separation of the abutting tongues 15 and notches 20.

Having now described my invention, I claim:

A paper receptacle having a bottom and 95 four diverging walls, the two side walls having wide tapering end flaps of single thickness and having inwardly folded upper edge flaps the ends of which are provided with substantially rectangular notches to present 100 abutments, and having free tongues extending from their ends, the two end walls having upper edge flaps folded inwardly over the wide end flaps of the side walls and over said free tongues, the end corners of the said 105 flaps of the end walls having tongues the ends of which abut the edges of the notches of the side wall edge flaps, the upper edges of the tapering end flaps of the side walls and said free tongues extending snugly along the 110 inner surfaces of the folds of the end wall flaps and resisting outward swing of the flaring side walls and consequent separation of the abutting tongues and notches.

In testimony whereof I have affixed my 115 signature.

ELIE W. LABOMBARDE.
